UNITED STATES PATENT OFFICE

143,059

DESIGN FOR A HAND TOY

Earl W. Coble, Waterville, Ohio, assignor to Dudley W. Moor, Jr., and Eugene M. Belknap, both of Toledo, Ohio

Application March 5, 1945, Serial No. 118,266

Term of patent 14 years

(Cl. D34—15)

To all whom it may concern:

Be it known that I, Earl W. Coble, a citizen of the United States, and resident of Waterville, in the county of Lucas and State of Ohio, have invented a new, original, and ornamental Design for a Hand Toy, of which the following is a specification, reference being had to the accompanying drawing, forming a part thereof.

In the drawing, Fig. 1 is a side view of a hand toy showing my design with the toy in upright

position, and Fig. 2 is an enlarged top end view thereof.

The characteristic feature of my new design resides in the arrangement of block-like members of contrasting colors on a spiral wire, all as illustrated.

I claim:

The ornamental design for a hand toy, substantially as shown and described.

EARL W. COBLE.
